UNITED STATES PATENT OFFICE

ABRAM N. PASMAN, OF WATERBURY, CONNECTICUT, ASSIGNOR TO SCOVILL MANUFACTURING COMPANY, OF WATERBURY, CONNECTICUT

BALL COCK

Application filed May 12, 1930. Serial No. 451,698.

This invention relates to ball cocks and more particularly to a valve structure adapted for use to control the admission of water to a tank or other receptacle for flushing 5 toilets or the like, the present structure being an improvement over the ball cock shown in my prior Patent No. 1,604,782 granted October 26, 1926.

In this type of structure it is necessary 10 that the valve controls the admission of water into a tank or the like and a float is provided in the tank to effect the closing of the valve when the water has reached a predetermined level. As the water entering the tank 15 is under pressure, the valve must be closed against this pressure, and in order that the float may always act positively to effect complete closing of the valve, it is desirable that the total resistance offered by this pressure 20 be reduced as much as possible. This pressure is, of course, due to the pressure of the water in the mains or system which supplies the tank and naturally varies to a considerable extent depending upon the particular 25 system in connection with which the valve is employed and also depending upon the amount of water being used at the time of operation of the valve which obviously causes a variation in the amount of pressure 30 in pipes.

One object of this invention is to provide 35 a ball cock in which the resistance opposing the closing of the valve shall be reduced to a minimum.

Another object of the invention is to provide 40 a ball cock wherein the valve will always be closed positively and effectively when the water in the tank has reached a predetermined level regardless of the pressure obtaining in the supply pipe.

Another object of the invention is the provision 45 of a ball cock in which the valve not only will be closed positively and effectively, but also in which the water will be conveyed to the tank and to the bowl in such a manner that the usual objectionable noise will be avoided.

To these and other ends, the invention 50 consists in the novel features and combinations

of parts to be hereinafter described and claimed.

In the accompanying drawing:

Fig. 1 is a central longitudinal sectional view of the ball cock; 55

Fig. 2 is a similar view of the upper portion of the device, but showing the valve in open position;

Fig. 3 is a top plan view of the upper end 60 of the ball cock; and

Fig. 4 is an enlarged sectional view of certain of the parts thereof.

To illustrate a preferred form of my invention, I have shown a ball cock such as is customarily employed for flushing a toilet 65 and which is normally installed within the usual flushing tank, the bottom of which is shown in a fragmentary way at 10. Entering an opening 11 in the bottom of the tank, is the usual supply pipe 12 which makes a 70 water-tight connection with the tank by means of the gasket 13.

The fitting or housing for the parts of the valve comprises an inlet pipe 14 in this instance having a threaded connection with 75 the supply pipe 12, this inlet pipe having an external spirally disposed groove 15. To the upper end of this pipe is secured a valve casing 16 having a skirt portion 17 which surrounds the upper end of the pipe 14 and is 80 spaced therefrom. A sleeve 18 is secured to the lower portion of the skirt 17 which sleeve surrounds the spirally grooved portion 15 of the inlet pipe 14.

Within the valve casing 16 there is provided 85 an annular wall portion 19, which provides a socket to receive an apertured valve seat member 20, this member being clamped against a flange on the member 19 by the upper end of the inlet pipe 14 which has a 90 threaded connection with the annular wall 19. The valve casing 16 is also provided with a boss or enlargement 21 which provides a passage 22 between the chamber at the outlet end of the seat member 20 and the sleeve 18, so 95 that the entering water may flow upwardly through the pipe 14, through the apertured valve seat member 20, through the passage 22, and downwardly within the sleeve 18 around the spiral grooves of the pipe 14 into 100

the tank. At the upper end of the valve casing 16 is provided a lever 23 pivoted in the casing at 24, this lever having an arm 25 secured thereto, upon the end of which arm is mounted the usual ball float (not shown) which controls the valve according to the level of water in the tank as will be explained hereinafter. This lever is provided with a toe portion 26 which operates the valve. As the parts heretofore described are shown in my prior patent referred to above, no further description thereof is deemed necessary.

Within the upper end of the valve housing 16 is mounted a cup-shaped member 28 having an opening 29 in the bottom portion thereof through which passes a valve stem 30, having an enlarged portion 31 at its lower end to which is secured a valve 32 by means of a screw threaded collar 33, this valve being adapted to seat upon the valve seat member 20 and control the flow of water through the aperture thereof.

Loosely surrounding the valve stem 30 so as to be movable thereon is a flanged collar 34 having upon its upper surface a member 35 of suitable packing material such as felt or the like designed to make relatively tight contact laterally with the wall of the casing 16 and also with the valve stem 30 so as to substantially prevent the passage of water upwardly through the opening 29 in the bottom of the cup or between the wall of the cup and the wall of the housing 16. As shown in Figs. 1 and 2, the peripheral edge of the member 34 is seated against an internal shoulder 36 in the upper portion of the housing 16 so that this member and the packing 35 is held between this shoulder and the bottom of the cup 28. It will be understood, therefore, that the valve stem 30 and valve thereon enjoys a reciprocating sliding movement through the flange 34 and packing 35.

Upon the upper end of the valve stem 30 is secured a head 37 having a stirrup 38 thereon within which is disposed the end 26 of the lever 23, the end 26 being of such form that it will contact with the upper portion of the stirrup to move the valve upwardly when the arm 25 of the lever is moved downwardly and will contact with the head 37 to move the valve downwardly when the arm 25 is moved upwardly under the influence of the float as controlled by the level of the water in the tank.

The upper end of the cup member 28 is cut away at 39 and 40 to provide clearance for the lever 23 and also for the pivot 24 which in this instance is a pin passed through apertures in lugs 41 and 42 formed on the wall of the casing 16 at the upper end thereof. The end of this pin is curved as shown at 43, and when in position is adapted to snap over the lip 45 to hold the lever 23 in place. The cup member will be held in place by engagement of the pin 24 with the shoulder 40.

The valve casing 16 is provided with an internal shoulder 47 adapted to guide the valve member in its movements and between this shoulder and the flanged collar 34 is a chamber 48 from which leads a refill pipe 49. The construction and operation of this refill pipe and associated parts is the same as substantially shown in my prior Patent No. 1,604,782 and hence no further description thereof is deemed necessary.

The operation of my improved ball cock is as follows: In Fig. 1 the parts are shown in the position which they assume when the flush tank is filled to the desired level and the valve 32 seated upon the seat member 20 closing the aperture therein so that no water flows through the inlet pipe 14. This is the normal position of the parts when the toilet or other fixture is not in use. When the toilet is flushed the water will be drawn from the flush tank as is well understood causing the arm 25 to move downwardly raising the lever 26 which contacts with the stirrup 38 and raising the valve 32 from its seat, the valve stem being moved through the packing 35 and through the opening in the cup member 28. It will be understood that the greater portion of the water entering through the aperture in the seat member 20 passes through the passage 22 and downwardly through the sleeve member 18 around the spiral grooves 15 into the tank. Some of the water, however, passes upwardly into the chamber 48 and thence through the refill pipe 49 to the bowl. When the tank has been filled to the desired level, the float on the end of the arm 25 will raise this arm to a sufficient extent to again seat the valve 32 so as to close the aperture in the seat member 20 against the passage of additional water.

It will be apparent that this valve member 32 must close against the pressure of the water in the inlet pipe 14. However, as the supply water also passes into the chamber 48, there will be pressure above the valve member 31 so that the effective resistance of the water pressure to the closing of the valve will only be that over an area equal to the cross-sectional area of the valve stem 30. If, however, the flange collar 34 and packing 35 were secured to the valve stem to move therewith, the water pressure in the chamber 48 would resist downward movement of this member and therefore would resist the closing of the valve. However, as the stem 30 is arranged to slide through the members 34 and 35, and as these members are held in a stationary position, the pressure of the water in the chamber 48 aids rather than opposes the closing of the valve with the effect before mentioned that the valve is resisted only by the water pressure on an area equal to the cross-sectional area of the stem 30. This stem may be made relatively small so that the resistance of the water pressure to the

closing of the valve will be correspondingly small and the valve will always be positively and effectively closed regardless of the fact that the water pressure in the supply pipes 6 may at certain times be relatively high. This often occurs at night for instance when very little water is being used, at which time and in some instances where the water pressure in certain localities was very high some 10 difficulty has been experienced in the past in securing positive closing of the valve. Due to the fact that the spirally grooved external surface of the inlet pipe 14 retards the course of the water to some extent, a back pressure is 15 produced in the chamber 48 which renders my improvement particularly advantageous in the form of fixture which I have illustrated. It will be obvious in this connection that if the packing member were secured to 20 and moved with the valve and valve stem, this back pressure would offer considerable resistance to the closing of the valve.

While I have shown and described a preferred embodiment of my invention, it will 25 be understood that it is not to be limited to all of the details shown, but is capable of modification and variation within the spirit of the invention and within the scope of the appended claims.

30 What I claim is:

1. A ball cock comprising a casing having a chamber therein, an inlet pipe communicating with said chamber, a valve within said chamber controlling the communication 35 between it and the inlet pipe, a stem secured to said valve, a packing member surrounding the stem through which the stem moves, said packing member being secured in the casing and contacting with the wall thereof, 40 means for holding said packing member in place comprising a cup-shaped member secured in the mouth of the casing and having its lower portion bearing against the upper face of the packing, a lever to operate the 45 valve, and common means for pivoting said lever to the casing and holding said cup-shaped member in place.

2. A ball cock comprising a hollow casing open at its upper end, an apertured member 50 therein, a valve for controlling said aperture, a cup-shaped member mounted in and closing the upper end of the casing, said valve being provided with a stem extending upwardly through said cup-shaped member, a packing member surrounding the valve stem at an intermediate point within the casing, and means for supporting said packing member from the casing, said valve, valve stem, cup-shaped member and packing member being insertable and withdrawable as a unit from said casing.

3. A ball cock comprising a hollow casing open at its upper end, an apertured member therein, a valve for controlling said aperture, a cup-shaped member mounted in and closing

the upper end of the casing, said valve being provided with a stem extending upwardly through said cup-shaped member, a packing member surrounding the valve stem at an intermediate point within the casing, means for supporting said packing member from the casing, a lever for actuating said valve stem, and common means for supporting said lever for actuation of said stem and securing said cup-shaped member in the casing.

4. A ball cock comprising a hollow casing open at its upper end, an apertured member therein, a valve for controlling said aperture, a cup-shaped member mounted in and closing the upper end of the casing, said valve being provided with a stem extending upwardly through said cup-shaped member, a packing member surrounding the valve stem at an intermediate point within the casing, means for supporting said packing member from the casing, said valve, valve stem, cup-shaped member and packing member being insertable and withdrawable as a unit from said casing, a lever for actuating said valve stem, and common means for supporting said lever for actuation of said stem and securing said cup-shaped member in said casing.

5. A ball cock comprising a casing having a chamber therein, an inlet pipe communicating with said chamber, a valve within said chamber controlling the communication between it and the inlet pipe, a stem secured to said valve, a packing member surrounding the stem through which the stem moves, means for holding said packing member in place, a lever to operate the valve, and common means for pivoting said lever to the casing and holding said packing member holding means in place.

6. A ball cock comprising a casing having a chamber therein, an inlet pipe communicating with said chamber, a valve within said chamber controlling the communication between it and the inlet pipe, a stem secured to said valve, a packing member surrounding the stem through which the stem moves, a cup-shaped member telescopically received in the mouth of the casing and having its lower portion bearing against the upper face of the packing, a valve operating lever extending into said cup-shaped member, and common means for pivotally supporting said lever and holding said cup-shaped member against movement out of said casing.

In witness whereof, I have hereunto set my hand this 8th day of May, 1930.

ABRAM N. PASMAN.
